UNITED STATES PATENT OFFICE.

WILLIS BROWN, OF OGLESBY, ILLINOIS.

TESTING DEVICE FOR SPARK-PLUGS.

1,170,407.

Specification of Letters Patent.

Patented Feb. 1, 1916.

Application filed November 17, 1914. Serial No. 872,597.

To all whom it may concern:

Be it known that I, WILLIS BROWN, a citizen of the United States of America, residing at Oglesby, in the county of La Salle and State of Illinois, have invented new and useful Improvements in Testing Devices for Spark-Plugs, of which the following is a specification.

This invention relates to improvements in testing devices for the spark plugs of hydro-carbon engines and has particular application to a portable testing device.

In carrying out the present invention, it is my purpose to provide a device of the class described which may be readily and conveniently applied to the spark plug when it is desired to determine whether or not the current is passing through the plug, without danger of shock to the operator.

It is also my purpose to provide a device of the class described which may be conveniently handled and stored in a small space when not in use and which will embody few parts and these so correlated and arranged as to render the possibility of derangement practically *nil*.

With the above and other objects in view, the invention consists in the construction, combination and arrangement of parts hereinafter set forth in and falling within the scope of the claims.

In the accompanying drawing, Figure 1 is a view in front elevation of a spark plug testing device constructed in accordance with the present invention. Fig. 2 is a view in edge elevation of the device. Fig. 3 is a bottom plan view. Fig. 4 is a top plan view. Fig. 5 is a fragmentary vertical sectional view through the device.

Referring now to the drawing in detail, 1 designates the body of the device, which, in the present instance, is substantially T-shaped comprising a head 2 and stem 3 formed of any suitable insulating material such, for instance, as fiber. The outer face of the head 2 is cut out to form a concaved recess 4 alining with the stem 3 of the body, while secured to the outer surface of the head 2 at opposite sides of the recess 4 are contact plates 5, 5 respectively. These plates 5 are constructed of suitable metal capable of conducting an electric current and, in the present instance, the end portions of each plate are upturned as at 6 to lie within the groove 4 and against the end of the head respectively.

Formed in the stem 3 at the junction of the latter with the head 2 is a transversely disposed opening 7 and formed in the edges of the stem at opposite sides of the opening 7 are apertures 8 communicating with the opening at diametrically opposite points. Formed in the head 2 at opposite sides of the recess 4 are apertures 9 corresponding to the respective apertures 8 and formed in the outer edge of the head 2 are grooves 10 communicating with the adjacent ends of the respective apertures 9, the grooves 10 opening onto the inner surfaces of the respective contact plates 5.

Passed through the apertures 9 are conducting wires 11 each having one end thereof lying within the adjacent groove 10 and soldered or otherwise secured to the inner surface of the particular contact plate 5 and the opposite end passed through the adjacent aperture 8 in the stem 3 and extending into the opening 7 to provide a terminal 12. These terminals 12 are spaced apart within the opening 7 and disposed diametrically opposite one another to form a spark gap 70 75 across which the spark is adapted to jump when the device is in use.

In practice, the contact plates 5, 5 are placed in contact with the spark plug to 85 electrically connect with the respective electrodes of the plug and if current is flowing such current will pass through the plates 5 and wires 11 and jump across the gap between the terminals 12 and produce a spark 90 in such gap which spark being visible through the opening 7, notifies the operator that the current is flowing. In the use of the device, the stem 3 constitutes a handle whereby the device may be conveniently applied to the plug. 95

I claim:

1. A testing device for spark plugs comprising a substantially T-shaped body having an opening formed therein, contact plates on the head of said body and spaced apart, and conducting wires connected with said plates respectively and extending into said sight opening and spaced apart therein to form a spark gap.

2. A testing device for spark plugs comprising a substantially T-shaped body having a recess formed in the outer edge of the head thereof approximately centrally of such edge, contact plates secured to said edge 110 of the head at opposite sides of the recess therein, said body being formed with a sight

- opening, and conducting wires connected with the respective plates and extending into said sight opening therein to form a spark gap.
5. 3. A testing device for spark plugs comprising a substantially T-shaped body having a sight opening formed therein at the junction of the stem and head and having a groove formed in the outer edge of the head thereof centrally of said head, contact plates secured to the outer edge of said head at opposite sides of the groove therein, and conducting wires connected with the respective plates and extending into said opening 10 and spaced apart therein to form a spark gap.
- 15
4. A testing device for spark plugs comprising a body formed with a head, and a stem and having a sight opening formed therein at the junction of the head and stem, 20 contact plates on the head and spaced apart and conducting wires connected with said plates respectively and extending into said sight opening and spaced apart therein to form a spark gap.
- 25

In testimony whereof I affix my signature in presence of two witnesses.

WILLIS BROWN.
